REFRIGERANT FOR REFRIGERATING PROCESSES IN WHICH THE REFRIGERANT HAS TO BE COMPRESSED

August Guyer, Zurich, Switzerland, assignor to the firm Escher Wyss Maschinenfabriken, Aktiengesellschaft, Zurich, Switzerland

No Drawing. Application March 27, 1933, Serial No. 663,104. In Switzerland April 5, 1932

4 Claims. (Cl. 62—178)

Ammonia, sulphur dioxide, and carbon dioxide are preferably used as refrigerants for refrigerating cycles or processes in which the refrigerant has to be compressed. The use of hydrocarbon compounds for the same purpose has also been proposed and, as some of the compounds in question are not combustible and at the same time, have suitable boiling points they have actually been used in practice, to a certain extent. The boiling point of the refrigerant used plays a very important part, especially in refrigerating plants with centrifugal compressors, such as have come more and more into use in recent times for refrigerating on a large scale. It is desirable for the temperature at which the refrigerant employed boils under atmospheric pressure to lie between the lowest and the highest temperature occurring in the process, because, when such is the case, the evaporator pressure is less than atmospheric pressure, while the liquefier pressure, on the other hand, is higher than the pressure of the atmosphere. This considerably facilitates the packing of the outwardly extending parts of the rotor of the centrifugal compressor, for it is then possible, for instance, so to connect the stuffing boxes of the compressor, by means of a pipe, or duct, that the medium which leaks from the stuffing box which is under a super-atmospheric pressure acts as a sealing medium for the stuffing box which is under a sub-atmospheric pressure. In this way, any entrance of air into the apparatus and any escape of refrigerant medium into the atmosphere can almost be completely prevented in practice, this being a matter of great importance from the standpoint of safe working.

The refrigerant to be compressed in a centrifugal compressor must, however, possess also as high a density as possible, or, which amounts to the same thing, as high a molecular weight as possible; the more this condition is satisfied the fewer the number of compressor stages required for a given refrigerating capacity and the easier it becomes to construct a simple and efficient compressor for the purpose in view.

The simultaneous satisfaction of the requirement of high molecular weight and the requirement of a favourably situated boiling point presents considerable difficulties inasmuch as just those substances which are of high molecular weight mostly have, as is well known, high boiling points also. The requirements mentioned will, however, be sufficiently satisfied if, according to the present invention, vinyl bromide ($\text{CH}_2:\text{CHBr}$) or its higher homologues alpha- and beta-bromo-

propylene, or alpha- and beta-chloropropylene, be used as refrigerants for refrigerating processes in which the refrigerant is to be compressed.

That the substances which it is proposed to use according to the present invention have not previously been suggested as refrigerants for refrigerating processes in which the refrigerant is compressed may be due to the known fact that they have a great tendency to polymerize and also, under certain circumstances, may decompose. I have however found as the result of experiment that such decomposition only occurs at temperatures which are higher than the highest temperature attained in refrigerating processes of the kind herein referred to. I have, further, found that polymerization does not take place in a closed apparatus which is impenetrable to light rays. Even in cases, however, in which it is not possible completely to exclude light, a refrigerant according to this invention can be stabilized by the addition of substances, such, for example, as iodine, which protect it from the action of light and prevent polymerization.

If, for instance vinyl bromide be used in a refrigerating plant of large capacity with a centrifugal compressor, a comparatively small number of stages may be used, on account of the great density of this substance. In addition to this, the favourably situated boiling point of vinyl bromide, namely $+16^\circ\text{ C}$. at atmospheric pressure, ensures that the evaporator pressure will lie not much below 1 atmosphere absolute (at 0° C . it amounts to 0.6 atmosphere absolute) while the pressure of the liquefier will lie somewhat above 1 atmosphere absolute (at 25° C . it amounts to 1.45 atmospheres absolute and at 30° C . it amounts to 1.7 atmospheres absolute).

Alpha-bromopropylene, the boiling point of which, at atmospheric pressure, is 59.5° C . may conveniently be used, if no lower temperature than 60° C . occurs in the liquefier, while beta-bromopropylene, the boiling point of which, at atmospheric pressure, is from 47° to 48° C ., is suitable when the liquefier temperature lies above 48° C . The boiling points of alpha-chloropropylene (36° C . at atmospheric pressure) and of beta-chloropropylene (23° C . at atmospheric pressure) both of which also have a high molecular weight, are just as favourably situated as the boiling point of vinyl bromide. As they, together with vinyl bromide and its higher homologues, are moreover connected by the vinyl group common to all these substances, all of them are closely related.

I claim:

1. The refrigeration method comprising centrifugally compressing and then expanding a bromide of one of the lower members of the vinyl group as refrigerant.
2. The refrigeration method comprising centrifugally compressing and then expanding vinyl bromide as refrigerant.
3. The refrigeration method comprising com-

pressing and expanding bromopropylene as refrigerant.

4. The refrigeration method comprising circulating a bromide of one of the lower members of the vinyl group as refrigerant through compression and expansion steps in the presence of iodine as a stabilizer to prevent polymerization. 5

AUGUST GUYER.
